UNITED STATES PATENT OFFICE.

WILLIAM G. A. BONWILL, OF DOVER, DELAWARE.

IMPROVEMENT IN LAMPS.

Specification forming part of Letters Patent No. 42,269, dated April 12, 1864.

To all whom it may concern:

Be it known that I, WILLIAM G. A. BONWILL, of Dover, in the county of Kent and State of Delaware, have invented certain new and useful Improvements in Lamps; and I do hereby declare the following to be a full and exact description of the same, reference being had to the accompanying drawings, making part of this specification, in which—

Figure 1 is a detached perspective view of the collar to be hereinafter described. Fig. 2 is a plan of my invention with a portion of the parts removed. Fig. 3 is a vertical section of the burner entire in the lines xx , Fig. 2.

Similar letters of reference indicate corresponding parts in the several figures, all of which are drawn on an enlarged scale to represent the invention more clearly.

This invention consists, first, in a novel construction of collar, by means of which hair may be supplied to the interior of the chimney above the cone in any desired quantity, said collar sliding either horizontally or vertically to graduate the capacity of the openings as required; second, in an improved device for elevating the wick and retaining the same in any position at which it may be desired to adjust it, all as will be hereinafter fully explained.

In order that others skilled in the art to which my invention appertains may be enabled to fully understand and use the same, I will proceed to describe its construction and operation.

In the accompanying drawings, A may represent the cup; B, the cone, and C a collar. This collar C operates in connection with a ring, C', which fits within the collar C, and which is formed with a flange, c, upon which the collar C rests, said flange adapting both collar and ring to be more readily secured upon or within the cup A by means of a spring-catch, a, which bears firmly against the flange c so as to retain the ring C' in a proper position when secured upon the cup. The collar C and ring C' are each provided with a continuous series of openings, c', which, by turning the collar C, may be placed in partial or full communication with each other or entirely closed, which turning of the collar C may be facilitated by the employment of a finger-piece, c². On the upper part of the collar C, and above the openings c', is formed

a ledge, c³, upon which the lamp-chimney is designed to rest. When the lamp is to be lighted, the collar C is to be turned so as to admit the full quantity of cool air to the interior of the lamp-chimney above the cone through the apertures C' of the collar, which prevents the chimney from being broken by too suddenly becoming heated, which has hitherto been of such frequent occurrence owing to the too rapid expansion of the inside wall of the chimney in excess of the outer, from the concentration of heat which must occur when the lamp is first lighted, experience having fully justified this conclusion. By the use of this improvement the inner wall is shielded all-around by a medium of air of nearly the same temperature as that in contact with the outer wall which passes rapidly between the flame and inner wall, so that this medium has first to be heated before the inner wall, which, being very slow, gives the chimney ample time to be heated, so nearly as soon externally as internally as to remove the greatest cause for the cracking of chimneys. After the chimney has thus been allowed to become gradually heated, the openings c' are to be closed far enough to admit only of that amount of air calculated to produce perfect combustion, which is most perfectly gained by this graduated fixture, increasing thereby the size of flame at least one-fourth as well as preserving chimneys. The collar C and ring C' may be securely connected together, and the movement of the former upon the latter limited by a rivet or rivets, c⁴. The collar C C' c' may be permanently attached to the lamp, or it may be made and sold separately to be applied to lamps already in use.

D represents a spiral spring secured to the floor of the cup A, or to both it and the wick-tube E, and in connection with which spring works the catch a, by which the cone B, as well as the collar C C', may be held within the cup A. The wick-tube is formed in two sections, E E', the former of which is rigidly attached to the floor of the cup, while the section E' is adapted to be slid vertically within or upon the former by a ratchet-wheel, e, which is keyed upon a shaft, e', and which works in the teeth of a rack, e², formed upon the sliding tube E'.

The object of this improvement is that when a small light is desired, the tube E' may

be run up to nearly the top of the cone B, (which point is fixed so that the tube will not go above,) so that the air in passing out of the aperture in the top of the cone B must come in contact with the flame to produce perfect combustion, and thereby get rid of that nuisance which always occurs when the flame is low in all lamps heretofore made and in use, which smell of oil is caused by the wick being so far below that point where it must be for the amount of air to come in contact with it to produce that complete combustion which is effected when the flame is the largest. Thus you can make of any large lamp a night-lamp, and one free from the unpleasant odor. For a full flame the tube is to be turned down to its lowest point. A milled head, e^3 , may be employed to facilitate the operation of the sliding-tube E'.

F represents a strong spiral spring, secured to the stationary wick-tube E, or between it and the bottom of the cup A, and supporting and pressing inward a shaft, F', upon which are rigidly secured the wick-elevating ratchets $f^1 f^2$, which being pressed through suitable slots in the tube E' constitute sustainers for the wick, as well as elevators therefor. The spring F occupies a very small space and provides great elasticity within a very limited compass. Upon the end of shaft F' is secured a milled head, f^3 , by turning which the wick may be elevated or lowered with facility.

The chimney-preserved above described may be used upon any of the lamp-burners now

in use, or attached permanently or otherwise to any new burners that may be made hereafter.

Having thus described my invention, the following is what I claim as new therein and desire to secure by Letters Patent:

1. The collar C C' c^1 , constructed, as described, with a series of apertures extending completely around it, variable in capacity by the action of the register and adapted to admit a supply of cool air to the interior of the chimney immediately above the cone or deflector from the medium outside (without first passing into the cup of burner) to prevent the chimney from being cracked or broken by sudden heat.

2. Being aware that springs have before been employed in various ways to press the wick and the elevating-wheels into close contact, I disclaim this general principle; but I claim the specific combination and arrangement of the spring F, spur-wheels $f^1 f^2$, shaft F', and slotted wick-tube E, when the said spring is firmly secured by its lower part, f^3 , to the floor of the shell A, is formed with a double coil, $J^1 J^2$, and rises in two standards, $J^3 J^4$, embracing the shaft F' in close proximity with the respective spur-wheels $f^1 f^2$, as herein described.

WM. G. A. BONWILL.
